REFRIGERATOR LATCH

William O. Burke, Rockford, Ill., assignor to National Lock Co., Rockford, Ill., a corporation of Delaware

Application April 25, 1942, Serial No. 440,517

5 Claims. (Cl. 292—332)

This invention relates to latches, and the embodiment thereof here disclosed is designed particularly for use on refrigerators. The principles of my invention, however, may be embodied in latches designed for various uses.

One of the primary purposes of my present invention is to provide a latch wherein the latch bolt when retracted to clear the keeper and permit the door to open will be automatically locked or retained in retracted position, so that it will not engage the keeper upon closing movement of the door but will, just as it passes the nose of the keeper, be automatically released and projected into latching engagement with the keeper. By retaining the latch bolt in retracted position, the slamming of the door, which is usually necessary to force the bolt past the keeper, is obviated so that a slight push only sufficient to swing the door on its hinges to closed position is necessary.

My invention also contemplates the provision of a latch which is strong, durable and reliable in operation and which can be manufactured and installed at a reasonable cost.

For the purpose of facilitating an understanding of my invention, I have illustrated a preferred embodiment thereof on the accompanying drawing.

Referring to the drawing,

Fig. 1 is a sectional view through a door provided with a latch embodying my invention;

Fig. 2 is a view similar to Fig. 1 showing the latch bolt retained in retracted position; and

Fig. 3 is a view taken on the line 3—3 of Fig. 2 showing the latch in elevation.

Referring to the drawing more in detail, reference character 5 indicates generally the door jamb of a refrigerator cabinet upon which is adjustably mounted the support 6 for a keeper 7 having an inclined bolt engaging face 8.

The door, which is preferably of metal construction, comprises the inner wall 9, the outer wall 11, and a face plate 12 opposed to the door jamb and provided with an opening 13 through which the keeper may project into the door body. A sealing strip 14 carried by the door is adapted to seal against the face of the jamb, and the space between the door walls is customarily filled with insulating material (not shown).

The latch mechanism, which is disposed within the door, comprises a frame or housing 15 anchored to the door walls and providing a guide for the latch bolt 16 having a latching portion 17 made preferably of plastic composition and shaped to engage the face 8 of the keeper 7, as

illustrated in Fig. 1. It will be observed from this figure, and more particularly from Fig. 2, that the engaging face 18 of the latching portion 17 is inclined so that as the bolt is projected across the face 8 of the keeper, the door will be drawn into snug sealing relation with the jamb. The bolt is normally urged into projected position by an expansion spring 19 interposed between the head of the bolt and a pin 21 anchored in the frame 15 and extending through a slot 22 in the shank of the bolt, so as to permit reciprocatory movements of the bolt.

The bolt may be manually retracted into unlatched position by exerting an inward pressure upon the exposed end of a plunger 23 mounted in the front wall 11 of the door in position to actuate a bell crank lever 24 fulcrumed on a pin 25 with one arm engageable with a pin 26 carried by the bolt, so that actuation of the bell crank lever in a clockwise direction will retract the bolt from the position shown in Fig. 1 to that shown in Fig. 2. Any other preferred means mounted upon the outer face of the door may be employed for actuating the plunger 23.

For the purpose of eliminating the exertion upon the door of a pressure sufficient to cause retraction of the bolt by engagement of its inclined outer end 27 with the inclined outer end 28 of the keeper and consequently provide an easy closing door, my improved latch includes means for locking or retaining the latch bolt in retracted position until the door reaches substantially closed position. For this purpose there is mounted upon a pin 29 extending through and between a pair of spaced ears 31 projecting from the body of the bolt, one end off a link 32. The opposite end of this link is pivotally connected by a pin 33 with a second link 34 which, in the form illustrated, consists of two legs bent to conform to the general contour of the forward end of the frame or housing 15 and pivoted therein upon a pintle 35 extending from side to side of the housing. A coil spring 36 mounted upon the pintle has one end anchored back of an abutment 37 struck inwardly from the housing and its other end engaged back of abutment plate 38 extending between and connecting the spaced legs of the link. This spring tends to swing link 34 in a counter-clockwise direction about the pintle 35 toward the position illustrated in Fig. 2.

My novel latch operates in the following manner:

Assuming that the door is latched in the closed position shown in Fig. 1, an inward thrust upon

the plunger 23 will retract the latch bolt into the position shown in Fig. 2, where it clears the keeper and permits the door to be swung open. This retracting movement of the bolt swings the pivot pin 33 connecting the links 32 and 34 so as to dispose the toggle formed by these links in dead center position with the pin 33 in alignment with the pin 29 and pintle 35. When this position is reached, the spring 36 forces the toggle beyond dead center into the position shown in Fig. 2 with the links at their point of connecting abutting against a shoulder 39 provided by a U-shaped plate extending between and riveted to the side members of the frame 15. The bolt is, therefore, held by this toggle mechanism in the retracted position shown in Fig. 2.

Upon closing movement of the door, the bolt in its retracted position clears the keeper 7, but when the door reaches substantially the position shown in Fig. 2, the abutment plate 38 carried by the link 34 is brought against the end of the keeper so as to swing the links away from the plate 38, thereby breaking the toggle to release the bolt which is then projected by the spring 19 against the face 8 of the keeper, thus drawing the door into snugly closed position and latching it in that position.

It will be apparent from the foregoing that, since only a very slight force is required to throw the toggle past dead center position and release the bolt, only a correspondingly light pressure against the door is required to close it. This closing pressure is very much less than would be required to close the door by forcing the bolt past the keeper against the action of spring 19. An easy closing door is thus provided and injurious jars and strains upon the latch parts are minimized.

The structural details of the mechanism illustrated and described may be considerably modified without departing from the scope of my invention as defined in the following claims.

I claim:

1. In a refrigerator latch, the combination of a bolt adapted to engage a stationary keeper for holding a door in closed position, a spring for projecting said bolt, manually operable means for retracting said bolt against the action of said spring, and an over-center toggle mechanism pivotally connected at one end with the bolt for holding said bolt in retracted position, said mechanism being positioned in alignment with the keeper to be actuated by the extremity of said keeper upon closing movement of the door to thereby release said bolt.

2. In a refrigerator latch mechanism, the com-

bination of a bolt positioned to be engaged with a stationary keeper for holding a door in closed position, a spring urging said bolt into projected position, manually operable means for retracting said bolt, a pair of pivotally connected links, the outer end of one of said links being pivoted to the bolt and the outer end of the other link being stationarily pivoted, a spring for urging said links into over-center position upon retraction of the bolt to thereby retain said bolt in retracted position, one of said links being positioned to engage the keeper upon closing movement of the door whereby said links are moved past dead center in the opposite direction to release said bolt.

3. In a refrigerator latch, the combination of a bolt positioned to engage a stationary keeper for holding a door in closed position, a spring urging said bolt into projected position, means for retracting the bolt against the action of said spring, a link stationarily pivoted at one end, a second link pivoted to the bolt, the free ends of said links being pivotally connected together, a spring for urging said links in one direction into over-center position upon retraction of the bolt, and an abutment portion carried by one of said links in position to be engaged by the keeper upon closing movement of the door, whereby said links are moved past dead center in the opposite direction to release said bolt.

4. A refrigerator latch comprising a stationary keeper, a latch bolt mounted on a door, a spring for projecting said latch bolt into engagement with said keeper to hold the door in closed position, means for retracting said bolt, and a pair of links pivotally connected together, the free end of one of said links being pivoted to the bolt and the free end of the other link being stationarily pivoted to dispose said link in position to be engaged by said keeper upon closing movement of the door.

5. In a refrigerator latch, the combination of a bolt arranged to engage a keeper when in projected position, a spring for projecting said bolt, manually operable means for retracting the bolt, a pair of pivotally connected links, the free end of one link being pivoted to the bolt and the free end of the other link being stationarily pivoted so as to present a portion of said link in position to be engaged by said keeper upon closing movement of the door, and a spring for urging said links into over-center position upon retraction of the bolt, said links being adapted to be moved into over-center position in the opposite direction by said keeper against the force of said spring to thereby release said bolt.

WILLIAM O. BURKE.
